UNITED STATES PATENT OFFICE.

CLAUDIUS DORNIER, OF FRIEDRICHSHAFEN, GERMANY, ASSIGNOR, BY MESNE
ASSIGNMENTS, TO HIMSELF AND TO DORNIER METALLBAUTEN GESELLSCHAFT
MIT BESCHRANKTER HAFTUNG.

GIANT HYDROPLANE.

Application filed June 28, 1920. Serial No. 392,542.

To all whom it may concern:

Be it known that I, CLAUDIUS DORNIER, a citizen of Germany, residing at Friedrichshafen, Germany, have invented certain new 5 and useful Improvements in Giant Hydroplanes, of which the following is a specification.

My invention refers to flying-machines and more especially to giant hydroplanes 10 having the motor plant accommodated in the supporting planes.

According to the present invention the supporting planes as well as the motor plant arranged therein are supported by a few 15 strong struts rigidly fixed at the bases to the hull of the boat and with their upper ends to the supporting planes and the engine cases respectively. These struts being hollow and of large cross-section enable a 20 direct communication for the crew between the hull of the boat and the motor plant, the passage from the upper part of the flying-boat to the lower part thus becoming perfectly free from danger. Moreover the 25 rope-ladders and other wire bracings which increase the running resistance, are eliminated. The air resistance of the posts, moreover, is reduced either by making the tubes themselves stream lined or by providing the 30 more or less circular tubes with stream lined envelopes.

In order to further increase the useful space and to obtain a simple, but effective staying of the main supporting plane outside 35 the motor plant, the hull of the boat in the part situated below the motor foundation, a pair of self-supporting stub planes is fixed laterally to the hull. From the stub planes a number of auxiliary struts extend approxi- 40 mately to the center of each half of the supporting plane. It is advisable to arrange the struts of each side behind one another in a plane extending from the front to the back in such a manner that the larger portion 45 of each half of the supporting plane which is situated beyond the struts, remains self-supporting.

The drawing attached to this specification and forming part thereof, illustrates by way 50 of example a flying-boat embodying my invention in a purely diagrammatical manner, Figs. 1, 2 and 3 being a side-view, a top view and a front view, respectively, of a giant flying-boat.

The hull B is connected with the central 55 part of the main supporting plane A by means of four hollow posts F each provided with a stream-lined casing.

In the parts situated above each pair of 60 posts F, the main supporting plane A is expanded to form an engine casing a'. Each engine casing contains two motors C for driving the air propellers E. The hollow posts F are provided with rungs f' in order 65 to serve as shafts closed all round and thus to allow of persons passing through. The space intervening between the rear half of the post and the casing can contain piping, signalling traction ropes, telephone wires, etc. The part of the hull of the boat B situated 70 under the main supporting plane A and under the engine casings a respectively, carries two self-supporting stub planes b. Stays G slanting upwards lead from the outer edge of the stub planes b' to the main 75 supporting plane A in a plane extending from the front to the back. The dimensions are chosen in such a manner that about one-half to two-thirds of the main supporting plane on each side is self-supporting. The 80 two engine casings a are laid as near the plane of symmetry as possible so that the circles, described by the forward pair of propellers, almost coincide.

I claim:

1. In a flying machine in combination, a hull, a supporting plane above said hull, a motor plant disposed within said supporting plane and a hollow supporting strut of large cross section extending from said hull to the 90 portion of said plane accommodating said motor plant.

2. In a flying machine in combination, a hull, a supporting plane above said hull, a pair of motor plants symmetrically disposed within said supporting plane and a pair of hollow supporting struts of large cross-section 95 extending and forming passageways from said hull to each motor plant.

3. In a flying machine in combination, a hull, a supporting plane above said hull, a motor plant disposed within said supporting plane and a hollow streamlined supporting strut of large cross section extending from said hull to the portion of said plane 100 accommodating said motor plant.

4. In a flying machine in combination, a hull, a supporting plane above said hull, a

pair of motor plants symmetrically disposed within said supporting plane and a pair of hollow streamlined supporting struts of large cross section extending and forming 5 passageways from said hull to each motor plant.

5. In a flying machine in combination, a hull, a supporting plane above said hull, a motor plant disposed within said supporting 10 plane, a hollow supporting strut of large cross section extending from said hull to the portion of said plane accommodating said motor plant, a pair of stub planes fixed to the hull and auxiliary struts extending

from said stub planes to said supporting 15 plane.

6. In a flying machine in combination, a hull, a supporting plane above said hull, a pair of motor plants symmetrically disposed within said supporting plane, a pair of hollow supporting struts of large cross section 20 extending and forming passageways from said hull to each motor plant, a pair of stub planes fixed to the hull and auxiliary struts extending from said stub planes to said sup- 25 porting plane.

In testimony whereof I affix my signature.
CLAUDE DORNIER.
